UNITED STATES PATENT OFFICE.

AMOS CALLESON, OF BROOKLYN, NEW YORK.

DESIGN FOR A HOLDER FOR EARS OF CORN.

SPECIFICATION forming part of Design No. 24,668, dated September 10, 1895.

Application filed June 6, 1895. Serial No. 551,911. Term of patent 3½ years.

To all whom it may concern:

Be it known that I, AMOS CALLESON, a citizen of the United States, residing at the city of Brooklyn, in the county of Kings and State 5 of New York, have invented and produced a new and original Design for Table Implements and that class thereof known as Corn-Holders, of which the following is a specification, reference being had to the accompanying 10 drawings, forming part thereof, in which—

Figure 1 is a side elevation of a corn-holder made according to my design; and Fig. 2, an edge view of the same, these two views being deemed necessary to fully illustrate my de- 15 sign.

The leading features of my design consist in an elliptical handle A, which is united with the holder proper by two smaller elliptical portions B and C, and the holder composed 20 of a ring or rings D and the side arms E, which are extended at an acute angle to the diameter of the ring or rings D, and each in the same plane, and the ends F thereof being directed inwardly at an acute angle to the 25 sides or at a right angle to the said diameter of the ring or rings D, which when extended would pass through the center of the handle A. It will be observed that in my design a line drawn through the longitudinal center

of the loop A, which forms the handle of the 30 holder, would pass, also, through the longitudinal centers of the loops or elliptical portions B and C, and, also, through the centers of the ring or rings D, and when extended would be at all points equally distant from 35 the sides E E and from the ends of the inwardly-directed portions F, and the entire device is thus perfectly symmetrical in form, thus presenting to the eye the effect always produced by regular outlines and circular or 40 curved forms. It will also be observed that when viewed from the edge thereof, as shown in Fig. 2, my design presents a symmetrical form and ornamental appearance, though different from that when viewed from the side, as 45 shown in Fig. 1.

Having fully described my new and original design for corn-holders, I claim and desire to secure by Letters Patent—

The design for corn-holders, herein shown 50 and described.

In testimony that I claim the foregoing as my invention I sign my name in presence of the subscribing witnesses.

AMOS CALLESON.
